(57) **CLAIM**

The ornamental design for a spindle mounting plate for disc brakes, as shown and described.

DESCRIPTION

FIG. 1 is a front perspective view of the spindle mounting plate for disc brakes;

FIG. 2 is a top plan view thereof;

FIG. 3 is a bottom plan view thereof;

FIG. 4 is a right side elevation view thereof;

FIG. 5 is a left side elevation view thereof;

FIG. 6 is a front elevation view thereof; and,

FIG. 7 is a rear elevation view thereof.

The broken line showing of the six circular apertures is provided for the purpose of illustrating portions of the spindle mounting plate for disc brakes and forms no part of the claimed design.

1 Claim, 3 Drawing Sheets
